(57) CLAIM

The ornamental design for a case, as shown and described.

DESCRIPTION

FIG. 1 is a front perspective view of a case;

FIG. 2 is a front view of the case of FIG. 1;

FIG. 3 is a rear view of the case of FIG. 1;

FIG. 4 is a top view of the case of FIG. 1;

FIG. 5 is a bottom view of the case of FIG. 1;

FIG. 6 is a right side view of the case of FIG. 1; and,

FIG. 7 is a left side view of the case of FIG. 1.

The broken lines shown in the figures illustrate structure or features that form no part of the claimed design. The drawings include shading lines that represents contour and not surface ornamentation or color.
